UNITED STATES PATENT OFFICE

CONRAD B. KRAUSE, OF CLEVELAND, OHIO

REFRIGERATING APPARATUS

Application filed February 20, 1926. Serial No. 89,575.

This invention relates to refrigerating apparatus and more particularly to a portable apparatus adapted for cooling drinking water.

5 It is one of the objects of the invention to provide an apparatus of the type referred to, that will have its units so arranged that they will operate efficiently and will be adapted for convenient assembly and disassembly. A 10 further object of the invention is to provide an apparatus adapted to support a large container for the drinking water directly from the base of the apparatus, by means of columns which extend to the top and are provided with means for supporting the units in 15 a substantial manner.

A further object of the invention is to provide an apparatus of the type referred to in which the cooling coil for the refrigerant is 20 located adjacent the top of the apparatus and so exposed that there will be a free circulation of air around the coil, with the other units of the apparatus so located that they will not be affected by the heat which is dissipated from this cooling coil.

Other objects of the invention and the features of novelty will be apparent from the following description, taken in connection with the accompanying drawings, of which

25 Figure 1 is a side elevation of an apparatus embodying my invention, a portion of the casing being broken away to expose some of the units;

Figure 2 is an enlarged vertical section 35 through the upper part of the apparatus, the section being on the line 2—2 of Figure 3;

Figure 3 is a transverse section on the line 3—3 of Figure 2;

Figure 4 is a plan view of the supporting 40 ring for the water container;

Figure 5 is a detail section on the line 5—5 of Figure 1; and

Figure 6 is a detail plan of one of the supports for the cooling coil.

45 Referring to the drawings, and particularly to Figure 1, it will be noted that the apparatus comprises a base 10 that is mounted on casters 11 and carries three tubular pillars 12 which are secured to the base by bolts 13.

50 A bracket 14 is mounted on the base 10 and

preferably insulated therefrom by the blocks 15, the bracket being secured to the base by the bolts 16. An electric motor 17 is mounted on the base of the bracket 14 and a compressor 18 is secured to the bracket by the bolts 55 19, slots 20 being provided in the bracket to permit vertical adjustment of the compressor for the purpose of tightening or loosening the belt 21 by means of which the compressor is driven by the motor 17. The motor 60 17 is provided with a pulley 22 and the compressor 18 with a pulley 23 and the belt 21 operates on these pulleys.

The pillars 12 have brackets 24 secured thereon by means of the U-bolts 25 and these 65 brackets carry a plate 26 which serves as a partition to separate the space within the jacket 27 into two chambers, the space below the partition being the compressor chamber and the space above the partition being the 70 refrigerating chamber. The jacket 27 is supported on the base 10 and carries an ornamental flange 28 on its upper end.

The upper ends of the pillars 12 are tied together by a conical ring 29 which has radially projecting arms 30 that are secured to the tops of the pillars by means of bolts 31. A cover 32 has a central funnel-shaped depression 33 which rests on the ring 29 and is adapted to receive an inverted bottle 34, this 80 bottle containing a supply of drinking water.

A container 35 is supported on the partition 26 and serves as the refrigerating chamber for the drinking water. This container has a cover 36 secured thereon so as to be tightly 85 sealed thereto and a supply pipe 37 extends upwardly from the cover 36 and has its upper end telescoped over the flange 38 on the lower end of the funnel-shaped portion 33 of the cover 32. The water is supplied to the container 35, from the pipe 37, by means of a central opening 39 in the cover 36. A cooling coil 40 is arranged within the container 35 and suspended from the cover by means of a plurality of pairs of 90 supporting bars 41 between which the convolutions of the coil 40 are clamped.

A cooling coil for the refrigerant is shown at 42, this coil being of helical form and arranged between the flange 28 and the cover 100

32. The coil is supported by means of hang-
ers, each of which consists of a pair of bars
43 between which the convolutions of the coil
are clamped, one of the bars of each pair
5 having a laterally projecting arm 44 which
is secured to the upper end of a pillar 12 by
means of the bolt 31 thereon.

The refrigerating system comprises, in
addition to the compressor and coils 40 and
10 42, an expansion valve 45, which may be any
of the well known forms and which is con-
nected with the lower end of the coil 40 by
means of a pipe 46, and with the lower end of
the coil 42 by a pipe 47. The compressor 18
15 has a discharge pipe 48 in which there is an
oil separator 49, this oil separator having con-
nected therewith a pipe 50 which extends up-
wardly and is connected with the upper end
of the coil 42. The upper end of the coil 40
20 extends through the cover plate 36, as shown
at 51, and is connected by means of the pipe
52 with the intake of the compressor 18. By
this arrangement the compressed refrigerant
25 is conducted from the compressor 18 to the
upper end of the cooling coil 42 whence it
flows downwardly through this coil to the ex-
pansion valve 45 and from the latter to the
lower end of the refrigerating coil 40. The
30 refrigerant is conducted from the upper end
of the coil 40 back to the intake of the com-
pressor.

A discharge pipe 53, for the drinking water,
is carried by the cover plate 36 and extends to
a point near the bottom of the container 35.

35 A laterally extending pipe 54 has connection
with the pipe 53 above the cover 36, and ex-
tends through the jacket 27 and carries a
faucet 55 at its outer end. A waste tank 56
40 is secured to the jacket 27, below the faucet 55,
and may be drained by means of the cock 57.
The usual thermostat for controlling the
operation of the compressor in accordance
with the temperature of the water in the
chamber 35 is shown at 57'.

45 In practice the container 35 should be em-
bedded in suitable insulating material such
as cotton, cork, or any of the other commonly
used insulations.

From the foregoing, it will be seen that the
50 bottle 34, which constitutes a water supply
container, is supported from the base 10 by
means of the pillars 12, these pillars being
substantially secured together at their mid-
dle by the plate 26 and at the upper end by the
55 ring 29 so that a very rigid structure is pro-
vided. The parts are readily assembled and
disassembled and, when the cover 32 is re-
moved, the expansion valve 45 as well as the
connections to the coils 40 and 42 are easily
60 accessible through the top of the coil 42.
The coil 40 may be removed from the con-
tainer 35, without detaching it from the cover
plate 36. The space within the coil 42 is
left open so as to permit a free circulation of
65 air through the coil and since the heat, which

is dissipated by the coil, will tend to cause an
upward circulation of air, this heat does not
get to the refrigerating chamber 35.

The advantage of having the pipe 53 extend
70 to a point adjacent the bottom of the cham-
ber 35 and having the faucet 55 located above
this chamber is that the coolest water will
always be drawn from the chamber and when
the supply in the bottle 34 is exhausted, there
75 will still be a relatively large supply of cool
water remaining in the chamber 35 and pipe
37 which will be available for use when the
empty bottle has been replaced by a filled one.
In other words, water cannot be drawn from
80 the faucet 55 unless the level in the pipe 37
is above the faucet.

Having described my invention, I claim:

1. In refrigerating apparatus, the combi-
nation of a base, a plurality of pillars se-
cured to said base, a motor-driven pump 85
mounted on said base, a partition carried by
said pillars, a refrigerating chamber carried
by said partition, a member attached to said
pillars at the upper end thereof and adapted
to support a water-container, a cooling coil 90
surrounding said pillars and supported there-
by above said chamber, a refrigerating coil
in said chamber, and connections between said
coil and said pump whereby the refrigerant
is circulated.

2. In refrigerating apparatus, the combi-
nation of a base, a plurality of pillars on
said base, a refrigerating chamber adapted
to contain a refrigerating coil carried by said
pillars and having a water supply pipe ex-
100 tending upwardly, a member secured to the
upper ends of said pillars, a water-container
carried by said member and extending into
said pipe, and a cooling coil attached to said
pillars between said container and said cham-
ber and adapted to be connected to the re-
frigerating coil and a compressor.

3. In refrigerating apparatus, the combi-
nation of a base, a plurality of pillars on said
base, a refrigerating chamber adapted to con-
tain a refrigerating coil carried by said pillars
and having a water supply pipe extending
upwardly, a member secured to the upper
ends of said pillars, a cover plate carried by
said member and having a central down-
wardly extending funnel which enters said
pipe, a water-container supported in said
funnel and having an extension into said pipe,
a helical cooling coil surrounding said pipe
below said cover and adapted to be connected
110 to the refrigerating coil and to a compressor,
and an outlet pipe for withdrawing water
from said chamber having its discharge end
located above the level of the latter.

4. In apparatus of the class described, the
combination of a base, a plurality of pillars
carried by said base, a partition carried by
said pillars, a jacket enclosing the space be-
tween said base and said partition and ex-
tending above the latter, a pump carried by
125

said base, a refrigerating chamber carried by said partition above the same, a ring carried by said pillars above said jacket, a cover carried by said ring, and a helical cooling coil arranged between said cover and the upper end of said jacket, the space within said coil being open to permit a free circulation of air between the convolutions of the coil, and said cover being adapted to support a water-container.

10 In testimony whereof, I hereunto affix my signature.

CONRAD B. KRAUSE.
